FIG. 6.

INVENTOR:
William H. Schmitt
BY David E. Carlsen
ATTORNEY:

UNITED STATES PATENT OFFICE

WILLIAM H. SCHMITT, OF ST. PAUL, MINNESOTA

TRAFFIC SIGNAL

Application filed October 7, 1929. Serial No. 397,991.

My invention relates to traffic signals in general and more particularly to an illuminable and controlled signal most useful at street intersections. The main object is to provide a simple, highly efficient and inexpensive traffic signal operable in single or multiple units and in the latter case involving coordination of signals in series, as on an arterial street having heavy traffic. The features and construction of my device and its operation are hereinafter fully disclosed, references being had to the accompanying drawing, in which,—

Fig. 1 is a perspective view of a street, two intersections thereof and two of my devices suspended one above each of said intersections.

Fig. 2 is an end elevation of a preferred form of my traffic signal and Fig. 3 is a side elevation of Fig. 2, both views showing simultaneous signal means directing traffic in one general direction and stopping traffic at right angles thereto.

Fig. 4 is a longitudinal sectional elevation on a vertical plane through the device shown in Figs. 2 and 3, and additionally an electric diagram of cylinder rotating means.

Fig. 5 is a fragmentary perspective view of my improved signal cylinder, showing one end part thereof only.

Fig. 6 is an elevation of my device mounted on a post at the center of a street intersection.

Fig. 7 is a perspective view of a modified form of my signal cylinder.

Referring to the drawing, I have designated parts and things not directly associated with the device by capital reference letters and using otherwise reference numerals. In the drawing A designates a near street intersection (in Fig. 1) and B the next intersection beyond on a street designated 4th St., the cross street being designated Main Ave., for a more ready understanding of the other figures of the drawing. C are two corner buildings and D are posts at the curb line at the other two corners while E are suspension wires extending from said buildings and posts toward the center of the intersection over which said wires are shown connected

to and suspending my signal device (designated F in Fig. 1), preferably directly over the center of the intersection at a predetermined height normally such that all types of vehicles, street cars, etc., have ample clearance. In Fig. 6 my signal device is mounted on a post G in the middle of an intersection, the signal being high enough to be readily seen from all directions, for example, higher than a street car S and readily seen by pedestrians or drivers as in an automobile T approaching the intersection.

The preferred construction of my signal device is illustrated in Figs. 2, 3, 4 and 5 and the signal shown (F) in Fig. 1 should be assumed to be in the position of it shown in Fig. 3.

10 is a cylindrical signal medium having its ends closed also and is rotatably mounted as on a tubular shaft 11 at one end while the other end may have a solid shaft 12 journaled in an end wall 13A of a downwardly opening shell or housing 13 normally shielding or inclosing only the upper half of the said cylindrical member.

Shaft 11 is fixed to the lower edge portion of an end wall 13B of the shell 13. The lower perimeter of said shell is on a horizontal plane such that said shell or housing covers the upper half of the cylinder member and just above said rim may have cut-out portions or stenciled openings designating the names or numbers of the streets which intersect; for example, on the two opposite sides Main Ave. as in Fig. 3 designates the cross street and 4th St. on the ends thereof designate the other street seen in perspective in Fig. 1.

The entire cylindrical walls, and the corresponding end walls are divided on a common plane into upper and lower panels, of which the upper half of the cylindrical part 14R as in Fig. 4 may be red and the lower half 14G green, said walls being made of preferably translucent colored material. The end walls are each divided also into upper and lower halves, respectively green as 15G and red as 15R. Thus the lower half round panels at the ends of the cylinder expose red surfaces simultaneously and will signal traffic to stop

while simultaneously the lower panel of the cylindrical part is green signalling traffic to Go. Thus traffic on 4th St., as in Fig. 2 is signalled to proceed while cross traffic on 5 Main Ave. must stop.

At predetermined intervals the cylinder is rotated 180 degrees. To alternately expose red and green panels to traffic, as on 4th Street, while the end panels alternately expose green and red areas to signal traffic on Main Avenue. Obviously a series of any number of signals as on 4th Street may be used individually or co-ordinated to keep all traffic moving and all said traffic to stop 10 simultaneously to permit cross traffic on intersecting or entering streets.

All panels of the cylinder of each signal are illuminable from within as by an electric bulb 16 in a socket 16S on a rigid tubular 20 arm 17 connected with tubular shaft 11 and through which a cable 18 (see Fig. 4) for circuit wires extends to a source of current (not shown).

It will now be readily seen that the stenciled or cut out parts of shell 13 can be illuminated by the same light, in each case said illumination being of the opposite color than the traffic direction indication below it. For example, in Fig. 2 when the red end panel 25 15R is exposed to stop traffic, the name 4th St. is illuminated in green thereabove because the light penetrates the upper green panel 15G to show 4th St. distinctly, indicating to traffic on Main Street that the cross 30 street at this point is 4th St.

In Fig. 3 I have shown the lower or green half of the cylindrical member provided with extra lettering reading "Go on John and Smith Sts." This is for intersections where 40 for example a John St. and Smith St. cross Main Ave. at so-called long angles or acute angles to each other and traffic confusion is avoided. Thus drivers approaching Main Ave. on both said streets will proceed to 45 cross the intersection when the green signal so worded is exposed and while traffic on the cross street is simultaneously signalled to stop.

In Fig. 5 an end panel 15G is shown to be 50 hinged and can be swung open so a person can replace the bulb 16 within the signal when necessary.

In Figs. 2, 3 and 6, 19 is an auxiliary signal housing on top of shell 13 and having four 55 suitably colored illuminable lenses 20 exposed in four directions and adapted to be illuminated by any suitable means previously known in the art, at intervals, just before the changes in traffic direction are to be made.

In Fig. 1 a control box 21 is shown on one 60 of the posts D and from which circuit wires, as 22 in Fig. 4, lead to the signal, said wires being connected to a source of current 22B. The box has any suitable clock mechanism 65 represented as 23 in Fig. 4 over the face of

which a hand 24 is rotated to engage spaced contacts 25 in its path. As the hand passes over either contact circuit is closed to a motor 26 mounted in an outer housing 13H of shell 13, said motor turning the cylinder 180 degrees, by means of a train of gears 27 of which one is on the drum shaft 12. When arm 24 has passed a contact 25 the circuit is opened and motor 26 stops. Any other suitable electrically controlled device may be used to turn the cylinder 180 degrees at predetermined regular or variably timed periods.

In Fig. 6 a light frame 28 supports the signal above the top of post G rigidly and can be made to connect with the lower four 70 corners of the shell 13 in such a manner as not to obstruct clear vision of the signals.

In Fig. 7 I have illustrated a modified signal cylinder which may be cubular in shape or in elongated form prismatic as shown, the end and side panels being in alternate signalling positions corresponding to the signal means in the cylindrical type above described. Obviously the respective top and bottom panels 30 in this case will not have 90 much value as signal means but may be made of blank material and only the vertical panels used for signal purposes.

Various modifications may be embodied 95 without departing from the scope and spirit of my invention. For instance, in place of the illuminable street designating openings in the shell may be omitted and the said street names may be painted or applied on the various illuminated panels and just below the perimeter of the shell where they can be easily read. A further modification of the structure may consist in forming the housing 13 to continue below the horizontal center line as indicated by line 31 in Fig. 2, 100 said lower part necessarily of transparent material and completely inclosing the signal means.

I claim:

1. A traffic directing signal adapted to be 110 mounted over street intersections and comprising a cylindrical signal member with illuminable end and wall panels separated on a common plane, said cylinder mounted to rotate in a vertical plane, lighting means within said cylinder, a downwardly opening shell with end walls and said cylinder journaled in said end walls, the perimeter of the open part of said shell normally surrounding the cylinder in a horizontal plane and the plane of its axis to expose therebelow only one half of the cylinder including simultaneously only one half of each of its end walls.

2. The structure specified in claim 1 in 115 which the walls of said shell, above its perimeter, are provided with suitable street indicating or direction indicating letters or numerals.

3. The structure specified in claim 1 in 120

which the walls of said shell, above its perimeter, are provided with suitable street indicating or direction indicating letters or numerals forming openings illuminable from within said cylinder.

5 4. A traffic signal comprising a cylindrical illuminable member, the cylindrical part of which comprises two semi-cylindrical panels placed edge to edge, one panel of different color than the other, end walls in said member also illuminable and each formed of two semi-circular discs placed edge to edge on a common plane with the abutting edges of the semi-cylindrical panels, said latter panels also of different colors but in corresponding positions at both ends of the cylinder, a housing covering and surrounding the upper half of the signal cylinder and having journal means for rotatably mounting said cylinder at its end walls, means normally holding the cylinder with its panel dividing line in plane with the lower edge of said housing to expose one complete half of the signal cylinder below said plane and two opposite end 20 panels simultaneously, said means arranged to turn the signal cylinder one hundred and eighty degrees at predetermined intervals to expose alternately the respective half and end panels of the cylinder.

25 5. The structure specified in claim 4 in which the panels of one side of the signal cylinder comprise a main semi-cylindrical panel of translucent red material and end panels of green translucent material, the corresponding other half of the cylinder comprising a semi-cylindrical panel of green translucent material and end panels of red translucent material.

30 6. The structure specified in claim 4, and means in said signal cylinder for detachably retaining one of its panels to be moved to provide access to the interior of the cylinder.

35 7. A traffic directing signal comprising a cylindrical signal member rotatable on a horizontal shaft means, a housing inclosing the upper half of said signal member, the said signal cylinder divided into two semi-cylindrical illuminable wall members of contrasting colors, the ends of said cylinder comprising each two panels also illuminable and of contrasting colors corresponding to the colors of the first described panels, like 40 colored panels of the end and main cylinder walls arranged opposite to expose below said housing at one time, a semi-circular panel of one color and at both ends of the cylinder panels of the opposite color.

45 8. The structure specified in claim 7 and illuminating means within said cylinder, the said housing provided with means for suspending the signal over a street intersection with its opposite end panels exposed in direct line of one street and its cylindrical

50 panel exposed and visible to traffic only on the street or streets crossing the first mentioned street.

In testimony whereof I affix my signature.

WILLIAM H. SCHMITT.
